UNITED STATES PATENT OFFICE.

WILLIAM H. REIFF, OF PHILADELPHIA, PENNSYLVANIA.

BURGLAR-ALARM.

SPECIFICATION forming part of Letters Patent No. 690,997, dated January 14, 1902.

Application filed March 28, 1901. Serial No. 53,174. (No model.)

To all whom it may concern:

Be it known that I, WILLIAM H. REIFF, a citizen of the United States, residing in the city and county of Philadelphia, in the State of Pennsylvania, have invented certain new and useful Improvements in Burglar-Alarms, of which the following is a full, clear, and exact description, reference being had to the accompanying drawings, forming a part of this specification.

My invention has for its object the provision of a burglar-alarm of simple and efficient construction and operation, whereby a cartridge or an ordinary percussion-cap may be exploded by the act of opening a door or window adjacent to which the device is located.

The invention, as generally stated, comprises a suitable base or frame adapted to be fixed to a door or window jamb and provided with a cartridge or cap retainer, in combination with a spring-controlled plunger normally movable toward said retainer, and means, including a projecting arm, for temporarily locking said plunger in retracted position in opposition to the spring, whereby when the door or window is opened by an intruder it will impinge against and turn said arm in a manner to release the plunger, which, forcibly striking the opposing cartridge or cap, will fire the same, and thus sound an alarm.

The invention also comprises various novel features of construction, which will be hereinafter fully set forth.

In the drawings, Figure 1 is a perspective view of the device, showing the plunger thereof in elevated position. Fig. 2 is a vertical section thereof. Fig. 3 is a plan of the device as applied to a door.

A is a frame comprising in its preferred form a vertical base-plate a , provided on its outward side with a housing a' , at its upper end with an outwardly-extending lug a^2 , and at its lower end with a tubular projection a^3 , the whole being preferably cast in an integral piece. Extending fixedly from the back of the base is a screw a^4 , by means of which the frame may be readily affixed to a door (or window) jamb in proximity to the movable door, (or window-sash.) The base is also preferably provided with screw-holes a^5 for the insertion of additional screws, if desired. The tubular

projection affords a chamber for the reception of an ordinary blank cartridge C.

Loosely fitted to guide-openings in the respective ends of the housing is a plunger B, which is movable longitudinally toward and from the cartridge-chamber. This plunger is maintained movably depressed by the action of a strong spring b, which encircling the plunger bears at its lower end upon a lateral stud b' on the latter and on its upper end against the top of the housing. The lower end of the plunger is preferably pointed, as at b^x , to constitute a firing-pin, and its upper end is provided with a laterally-extending arm b^2 . The outer edge of the lug a^2 of the frame is provided with a V-shaped recess a^6 , so located as to receive the upper end of the plunger when the latter is drawn upward against the pressure of the spring and to afford on said lug two shoulders, upon either of which the arm may be turned in a manner to support the plunger in the elevated position.

To use the device above described, it is affixed to a door (or window) jamb D, as stated, the door (or window) D' is closed, the plunger is raised, the arm b^2 thereof is turned upon the lug a^2 , (either to the right or left, as required,) so as to extend into the path of the door (or window-sash) if the latter be opened, and a blank cartridge, as C, is inserted in the cartridge-chamber. This being done, if the door (or sash) be opened by an intruder the door (or sash) will strike the opposing arm b^2 and turn it upon the lug until it reaches the recess, whereupon the plunger, being freed, will be forced downward by the action of the spring in a manner to forcibly strike and thereby explode the cartridge.

In order that an ordinary paper percussion-cap may be used with the device, the plunger is provided at a point above the housing with a loose plate b^3 , between which and the opposing end of the housing a cap may be inserted when the plunger is raised. When the plunger is released, the arm b^2 forcibly strikes the plate and effects by the concussion the explosion of the cap.

I preferably, though not essentially, pivot on the outer wall of the housing a button E, which may be swung laterally outward, so as to perform the function of a check for the

partially-open door when the cartridge or cap has been fired.

I claim—

In a device of the character described, the combination with a support provided at its ends with a lug and a cartridge-chamber, respectively, and provided between said lug and chamber, with a housing, of a plunger slidingly fitted to the ends of said housing, a laterally-extending arm on said plunger adapted to be engaged with said lug, and a spring contained in said housing and tending

normally to maintain said plunger in close relation to the cartridge-chamber, together with a concussion-plate loosely mounted on 15 said plunger adjacent to the housing.

In testimony whereof I have hereunto affixed my signature in the presence of two subscribing witnesses.

WILLIAM H. REIFF.
